CLAIM

The ornamental design for an outdoor cart frame as shown and described.

DESCRIPTION

FIG. 1 is a perspective view of an outdoor cart frame showing my new design;
FIG. 2 is another perspective view thereof;
FIG. 3 is a front elevational view thereof;
FIG. 4 is a rear elevational view thereof;
FIG. 5 is a left side elevational view thereof;
FIG. 6 is a right side elevational view thereof;
FIG. 7 is a top plan view thereof;
FIG. 8 is a bottom plan view thereof; and,
FIG. 9 is a perspective view of the outdoor cart frame where the outdoor cart frame is in a configuration of use.
The dash-dash broken lines in FIG. 9 showing a handle are directed to environment that form no part of the claimed design. The other dash-dash broken lines in the drawings depict portions of the outdoor cart frame that form no part of the claimed design.

1 Claim, 9 Drawing Sheets
